ABSTRACT OF THE DISCLOSURE

An improved buoyant cake of soap which is formed of composite construction, the core consisting of an insoluble material such as plastic or wood, with the outer layer consisting of soap, which remains of a size large enough to be conveniently handled. A looped cord of plastic material is fastened to the insoluble core, which may be hung from the looped cord, when not in use.

FIELD OF THE INVENTION

The object of my invention is a buoyant bar of soap which is always large enough to conveniently handle, as long as any soap remains.

A further object is to make it possible to hang such a bar of soap from a hook, when it is not in use.

SUMMARY

In my invention, the bar of soap is of composite construction, including an insoluble core, a layer of soap surrounding said core, and a looped insoluble cord permanently attached to the core which protrudes past the layer of soap, permitting the soap bar to be hung from a hook in the bathroom, shower or kitchen.

BRIEF DESCRIPTION OF THE DRAWINGS

FIG. 1 is a perspective of the invention;

FIG. 2 is a cross-section along the line 2—2 of FIG. 1; and

FIG. 3 is a cross-section along the line 3—3 in FIG. 1.

DESCRIPTION OF THE PREFERRED EMBODIMENT

The composite soap bar consisting of an outermost layer of soap 20, an inner core 10 of insoluble material, and a looped cord 15 of insoluble material.

The core 10 is shaped so as to comfortably fit into the palm of the hands of the user with one section 12 being of a relatively convex shape, while the opposite section 14 is relatively flat. Cord 15 which is permanently fastened to the core at one end 16 protrudes past the layer

2

of soap 20 so that the bar may be hung from a hook when not in use. Preferably cord 15 is made of a plastic filament such as nylon.

The core 10 may be of solid structure such as wood or plastic, or it may be of hollow construction so as to minimize the cost of materials and to increase the buoyancy of the soap. Core 10 may also be made of a composite mix, such as foamed plastic, or plastic coated honeycomb paper.

Since obvious changes may be made in the specific embodiment of the invention described herein without departing from the spirit or scope thereof, it is indicated that all matter contained herein is intended to be interpreted in an illustrative and not a limiting sense.

Having thus described my invention, what I claim as new, and desire to secure by Letters Patent of the United States is:

1. A buoyant soap bar of composite construction, consisting of a core member, an outer layer of soap and a looped cord fastened to said core member and protruding through the layer of soap with said core member being so shaped in size as to be readily graspable as long as any soap remains on the outer layer of said core.
2. A soap bar of composite construction as described in claim 1 in which said core member is of hollow construction, so as to reduce the specific gravity of said bar to less than 1.0.
3. A composite soap bar as described in claim 2, in which said core member consists of a hollow plastic shape.
4. A soap bar of composite construction as described in claim 2 in which said core member consists of a plastic foam.
5. A soap bar of composite construction as described in claim 3 in which said looped cord is formed from an acrylic filament material.
6. A soap bar of composite construction as described in claim 1 in which said core is made of wood.
